(57) **CLAIM**

The ornamental design for an infrared heating lamp, as shown and described.

DESCRIPTION

FIG. 1 is a top plan view of a first embodiment of an infrared heating lamp, showing my new design;

FIG. 2 is a right side elevational view thereof;

FIG. 3 is a left side elevational view thereof;

FIG. 4 is a bottom plan view thereof;

FIG. 5 is a back elevational view thereof;

FIG. 6 is a front elevational view thereof.

FIG. 7 is a top plan view of a second embodiment of the invention;

FIG. 8 is a right side elevational view thereof;

FIG. 9 is a left side elevational view thereof;

FIG. 10 is a bottom plan view thereof;

FIG. 11 is a back elevational view thereof;

FIG. 12 is a front elevational view thereof.

FIG. 13 is a top plan view of a third embodiment of the invention;

FIG. 14 is a right side elevational view thereof;

FIG. 15 is a left side elevational view thereof;

FIG. 16 is a bottom plan view thereof;

FIG. 17 is a back elevational view thereof;

FIG. 18 is a front elevational view thereof;

FIG. 19 is a top plan view of a fourth embodiment of the invention;

FIG. 20 is a right side elevational view thereof;

FIG. 21 is a left side elevational view thereof;

FIG. 22 is a bottom plan view thereof;

FIG. 23 is a back elevational view thereof; and,

FIG. 24 is a front elevational view thereof.

The broken lines illustrate portions of the infrared heating lamp and forms no part of the claimed design.
